UNITED STATES PATENT OFFICE.

FRANK E. THORPE, OF VENICE, OHIO.

ALARM.

Application filed June 5, 1926. Serial No. 113,993.

This invention relates to an alarm, the general object of the invention being to provide means for exploding cartridges or the like when a door or other barrier is tampered with or a part, which is attached to the device to actuate the same, is moved by a person, animal or bird.

Another object of the invention is to so arrange the parts that the cartridges will be exploded in succession, with means for using cartridges of different calibre in the device.

A further object of the invention is to provide safety means for preventing operation of the trigger means until the trigger actuated lever is moved.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a top plan view of the device.
Figure 2 is an elevation thereof.

Figure 3 is a bottom plan view.

Figure 4 is a section on line 4—4 of Figure 1.

Figure 5 is a section on line 5—5 of Figure 2.

In these views, 1 indicates a supporting board or plate which is provided with the legs 2 so that it can be connected with a door frame or other support. A pair of brackets 3 is mounted on the upper face of the plate and each bracket carries a shaft 4 to which a hammer 5 is connected. A coiled spring 6 encircles each shaft and has one end connected with the hammer and the other end engages a part of the bracket. This spring tends to throw the hammer against a spring pressed firing pin 7 arranged adjacent one edge of the support. These pins pass through holes formed in a top plate 8 fastened to the plate 1 by the bolts 9 and in the plate 1. The holes in the plate 1 communicate with cartridge holding holes 10 formed in a bottom plate 11 which is held against the under side of the plate 1 by a bolt 12 provided with a wing nut 13. The holes 10 are of different sizes so as to

hold cartridges A of different calibre. After the cartridges have been fired by the hammer striking the pins 7, the nut 13 is removed from the bolt 12 so that the plate 11 can be removed and the firing cartridges pushed from the holes 10 and new cartridges put in their place. Then the plate 11 is put back and held in position by the bolt 12 and the nut 13. A trigger 14 is provided for each hammer, each trigger passing through a hole 15 formed in the base 1 and pivotally supported therein by a pin 16. An angle-shaped safety lever 17 is pivoted to the under side of the member 1 for each trigger, one end of each lever engaging the trigger and holding it in engagement with the hammer to hold the hammer retracted. A screw or pin 18 is carried by the other end of each lever 17 and passes through an arc-shaped slot 19 in the base 1.

A double lever 20 is pivoted intermediate its ends to the under side of the member 1, as shown at 21, and each end of said lever has an extension 22 hinged thereto. Either one of these extensions is adapted to be engaged by a door or other barrier, a portion of which is shown at B, but by turning this extension on its hinge, the device will be rendered inoperative, as the lever will not be engaged by the barrier when the barrier is opened. The lever 20 has a pair of clips 23 attached thereto, each of which is provided with a projection 24, one of which will engage one of the safety levers 17 on the initial movement of the lever 20 to move said lever out of the path of the trigger, while the other projection will move a slide 25 which will engage the other safety lever to move it out of the path of the other trigger. Then a bent arm 26 on the lever 20 will strike one of the triggers and move it to releasing position so that its hammer can be thrown against the firing pin to explode the first cartridge and then a part of the lever 20 will strike the other trigger and move it to releasing position to permit the other hammer to fire the second cartridge.

From the foregoing, it will be seen that I have provided simple means for exploding two cartridges, one after the other, so that the device can be used to frighten away thieves attempting to enter a building or the like or to frighten away animals, birds and the like which are attempting to enter hen-houses, coops or the like. Instead of having the lever 20 actuated directly by the

movement of the barrier, as in Figure 3, it may be actuated from a distance by attaching a rope 27 or cable to the lever and to the barrier or the like. By making the lever 5 double, as in Figures 1 and 3, either end can be used for actuation by a barrier.

After the device has been actuated, the hammers are cocked by hand, the triggers and safety levers being moved to hold them 10 cocked and then new cartridges are put in place so that the device will again be set.

It is thought from the foregoing description that the advantages and novel features of my invention will be readily apparent.

15 I desire it to be understood that I may make changes in the construction and in the combination and arrangement of the several parts, provided that such changes fall within the scope of the appended claims.

20 What I claim is:

1. An alarm device of the class described comprising a supporting member, spring actuated hammers carried thereby, car-

tridge holding means carried thereby, firing pins for the cartridges and actuated by the 25 hammers, a trigger for normally holding each hammer in retracted position, a lever adapted to be actuated by the opening of a barrier or the like and means for communicating the movement of the lever to the triggers to release the hammers.

2. An alarm device of the class described comprising a supporting member, a pair of spring actuated hammers carried thereby, cartridge holding means carried thereby, a 35 pair of firing pins for the cartridges actuated by the hammers, a trigger for holding each hammer in retracted position, a safety lever for holding each trigger against movement, a lever adapted to be actuated by a barrier or the like and means carried thereby for first moving the safety levers into inoperative position and then actuating the triggers in succession.

In testimony whereof I affix my signature.

FRANK E. THORPE.
